UNITED STATES PATENT OFFICE.

THOMAS WILBERN, OF CARPENTERSVILLE, ILLINOIS.

DOOR-HANGER.

SPECIFICATION forming part of Letters Patent No. 632,609, dated September 5, 1899.

Application filed March 23, 1899. Serial No. 710,163. (No model.)

To all whom it may concern:

Be it known that I, THOMAS WILBERN, a citizen of the United States, residing at Carpentersville, in the county of Kane and State 5 of Illinois, have invented certain new and useful Improvements in Door-Hangers, of which the following is a specification.

My invention relates to that class of door-hangers which is adapted to be used in connection with barn, warehouse, and other outside doors, and in which there is a trolley secured to the door and arranged to move upon a track, all of which will more fully hereinafter appear.

15 The principal object of the invention is to provide a simple, economical, and efficient adjustable door-hanger.

A further object is to provide a door-hanger by which a door may be moved and adjusted 20 to suit varying conditions.

Other objects of the invention will appear from an inspection of the drawings, specification, and claims.

The invention consists, principally, in a 25 door-hanger provided with an axle longitudinally adjustable thereon and a trolley-wheel rotatably mounted on said axle and prevented from having independent longitudinal movements.

30 The invention consists, further and finally, in the features, combinations, and details of construction hereinafter described and claimed.

In the accompanying drawings, Figure 1 is 35 a vertical sectional elevation of my improvement, taken on line 1 of Fig. 5; Fig. 2, a rear view of the frame portion of the hanger; Fig. 3, a front elevation of the base-plate by which the hanger is secured to a door; Fig. 4, a detail sectional elevation of the trolley-wheel and axle; and Fig. 5, a transverse sectional view, taken on lines 5 of Figs. 1 and 3.

In the art to which this invention relates it is highly desirable to provide a hanger for 45 outside doors and gates with means by which the door may be adjusted in vertical and horizontal planes, and the principal object of my invention is to provide simple and economical means to accomplish these results.

50 In constructing a door-hanger in accordance with my improvement I make a frame portion of the desired size and shape having

a depending arm A and a hooded portion A'. To support the hanger and furnish means by which the door B may be moved back and forth a frame portion is provided having a trolley-wheel C, rotatably mounted upon the bearing portion of an axle D, which has a threaded portion d, engaging with the threaded opening in the hooded part of the frame. 60

It is at times desirable to compensate for different thicknesses of the door, so that the trolley may be readily operated upon its track E without in any way cramping or deranging the door. In order to accomplish this result, 65 the axle has a threaded portion by which with its adjustable trolley it is moved longitudinally, so as to compensate for the different positioning of the track. In order to move and lock the axle and trolley in operative 70 position, the axle is provided with a polygonal head d' and a jam or lock nut d''. The trolley-wheel is mounted on the axle between the washers c and c', which are in turn held in place by means of a cross-pin c''. 75

It is desirable to provide means by which the trolley is prevented from "jumping" its track and to adjustably secure it so as to compensate for different widths of track. To accomplish these results a stop-lug G is provided, which is adjustably secured to the frame portion by means of the stud g and the nut g' passed through a slotted opening g² in the frame portion. Examining Fig. 1 it will be seen that the trolley can move upon the 85 track so as to compensate for differences in position and thickness of the door.

It is also desirable to raise and lower the door at either or both ends, and in order to accomplish this result a base-plate H is provided, having lugs h, through which screws or carriage-bolts h' may be passed to secure it to the movable door. This base-plate is provided with a set or sets of serrated teeth H' extending transversely across the same 95 and adapted to be engaged by serrated teeth a extending transversely across the depending arm of the frame portion, as shown particularly in Fig. 1. A bolt I is provided, which is passed through an elongated vertical opening a' in the frame portion and engages with the base-plate, so as to hold the parts together. When it is desirable to raise or lower the door at either or both ends, this securing-bolt is 100

loosened, so as to permit the disengagement of the serrations or teeth. The frame portion is then raised or lowered, as necessity may require, and the desired reengagement obtained.

From the foregoing description of construction and operation it will be seen that the door may be adjusted in vertical and horizontal planes at either or both ends to compensate for wear and different structural conditions, and that the trolley-wheel may be adjusted longitudinally, so as to compensate for any errors in positioning of the track, and, further, that means are provided for changing the guard-lug to accommodate any width of track. It will also be seen from the foregoing and from an inspection of the drawings that all of the elements that have been described contribute to one economical result—viz., the positioning and holding of the trolley on the track or the lateral positioning of the door. For instance, should the track E happen to be in a position above and to the left of its present position, as shown in Fig. 1, it will be seen that the trolley-wheel would have to be raised and also be moved inwardly. It is therefore necessary to have both of the adjustments above described—the vertical and horizontal—to perform this one result. The stop G also acts to prevent the trolley from jumping the track, and as the tracks vary in width and thickness it is necessary that this stop should also be adjustable.

I claim—

1. A door-hanger provided with an axle longitudinally adjustably mounted thereon, and a trolley-wheel rotatably mounted on said axle and prevented from having independent longitudinal movements, substantially as described.

2. A door-hanger comprising a frame portion provided with a depending arm, an axle longitudinally adjustably secured to the frame at or near its upper portion, and a trolley-wheel on such axle, substantially as described.

3. A door-hanger comprising a frame portion provided with a depending arm, an axle longitudinally adjustably secured to the frame at or near its upper portion, a trolley-wheel rotatably mounted on such axle, and means for vertically adjustably securing the

depending arm to a door, substantially as described.

4. A door-hanger comprising a frame having an upper hooded portion and a lower depending arm, an axle longitudinally adjustably secured in the hooded portion, a trolley rotatably mounted upon the axle, a base-plate adapted to be secured to a door, and means for vertically adjustably securing the base-plate and depending arm together, substantially as described.

5. A door-hanger comprising a frame portion provided with a depending arm, an axle longitudinally adjustably secured to the frame at or near its upper portion, a trolley rotatably mounted on the axle, a guard-lug adjustably secured to the frame beneath the trolley-wheel, and means for vertically adjustably securing the depending arm to a door, substantially as described.

6. A door-hanger comprising a frame provided with an upper hooded portion and a lower depending arm, an axle provided with a threaded portion engaging a threaded opening in the hooded portion, a trolley rotatably mounted on the axle, a base-plate adapted to be secured to a door and provided with transverse projections or teeth, transverse projections or teeth on the depending arm adapted to engage the teeth on the base-plate, and bolt mechanism for securing the base-plate and depending arm together, substantially as described.

7. A door-hanger comprising a frame provided with an upper hooded portion and a lower depending arm, an axle provided with a threaded portion adjustably engaging a threaded opening in the hooded portion, a trolley rotatably mounted on the axle, a base-plate adapted to be secured to a door and provided with transverse projections or teeth, transverse projections or teeth on the depending arm adapted to engage the teeth on the base-plate, bolt mechanism for securing the base-plate and depending arm together, and a lug adjustably secured to the frame portion beneath the trolley-wheel, substantially as described.

THOMAS WILBERN.
